United States Patent Office.

AMOS RANK, OF SALEM, OHIO.

Letters Patent No. 79,500, dated June 30, 1868.

IMPROVEMENT IN HARVESTERS.

The Schedule referred to in these Letters Patent and making part of the same.

TO ALL WHOM IT MAY CONCERN:

Be it known that I, AMOS RANK, of Salem, in the county of Columbiana, and State of Ohio, have invented certain new and useful Improvements in Harvesters, of which the following is a full, clear, and exact description, reference being had to the accompanying drawings, which make part of this specification, and in which—

Figure 1 represents a plan or top view of so much of a harvester, in which my improvements are embodied, as is necessary to illustrate my invention.

Figure 2 represents a view in elevation of the gearing side of the same, and

Figure 3 represents a side and edge view of the separating-rod or cut-off.

The invention herein claimed consists in a novel method of combining, with a harvester, a separating-rod or cut-off vibrating in a horizontal circular path, to separate the cut and falling grain from the gavel being discharged from the platform, substantially as hereinafter set forth.

In the accompanying drawings, which exemplify one practical way of carrying out my invention, a finger-beam, A, is shown as secured to a shoe, B, of suitable construction to be attached by a hinged connection to a two-wheeled harvester of approved construction, such, for instance, as the machine shown in my patent of June 26, 1866.

A reel-post, C, is bolted to a lug, b, on the shoe, in such manner as to permit the post to be adjusted backward or forward by a set-screw passing through the post, and a slot in the bracket.

A clasp, D, sliding on the reel-post, and held by the set-screw d, at any desired elevation, supports the shaft of an overhung reel, E.

A platform, F, by preference composed of slats arranged at right angles to the finger-beam, is provided with pins or studs, f¹, at its front corners. The pin f, on the divider side, is inserted in a socket in a lug attached to the finger-beam, while the one on the heel-end is inserted in a socket between two lugs on the shoe, and held by a pin, f². The platform is thus free to rise and fall on an axis parallel with the finger-beam. The pin f¹ in this instance is prolonged far enough to receive a bevel sector-gear or half pinion, h, gearing into a corresponding one, i, on a vertical shaft, I, turning in a socket, H, bolted to the shoe. A double-barrelled socket, J, slides vertically on this rod, and can be locked thereon, so as to turn with it, by means of a set-screw, j, or other equivalent device.

The vertical part of a bent rod, K, is inserted into the other barrel of this socket, and held by a set-screw, k, like the other one.

A socket, l, slides on the horizontal part of this bent rod, so that the socket can be moved lengthwise on the rod, or turned around it, as required, and be held in any desired position by a set-screw, l'. A separating-rod or cut-off, L, is inserted in this socket, and, by the devices above described, can be raised or lowered as desired, while preserving its parallelism with the ground, or be inclined at an angle thereto. The rod can also be adjusted on its vertical axis so as to be thrown forward closer to the reel, or farther backward on its reverse stroke. This plan gives me complete control over the adjustment of the separating-rod.

In fig. 3, I have shown a simpler plan, which works effectively, which consists in removing the double socket and bent rod, and in putting the socket l directly on the vertical rod I. This modification has all the adjustments of which the other is susceptible, except the rod cannot be inclined at an angle to the horizon, as in the other case. The rod I and separator are rotated, in this instance, by means of a lever, h', on the end of the shaft f¹, which lever is to be raised or lowered by means of suitable connections from the main frame, of any proper well-known form, adapted to the machine to which it is to be applied.

The finger-beam is to be provided with a cutting-apparatus of approved construction, and with a suitable divider, M.

In operation, as the machine advances the grain is swept back by the reel, severed by the cutters, and falls upon the platform, which occupies the elevated position shown in red lines in fig. 2. While the platform is in this position, the separating-rod or cut-off is turned back at right angles to the finger-beam, as shown in red

lines. When a gavel of sufficient size has accumulated, the driver lowers the lever h' , which drops the platform into the position shown in black lines, and discharges the gavel. As the platform descends, the shaft f^1 is turned, and through its gearing rotates the rod I , quickly causing the cut-off to swing in quickly above the platform and finger-beam, parallel with the latter, as shown in black lines. In this position the rod receives the grain which is cut and falling while the platform is dropped. As the platform is raised by the reverse movement of the lever h' , and the other parts of the mechanism, the cut-off is withdrawn out of the way, and the grain falls on the platform as before.

The red lines in fig. 1, behind the finger-beam, indicate the outlines of a solid fixed platform, which may be substituted for the slatted dropping one, when it is desired to convert the machine into a hand-raker.

What I claim as my invention, and desire to secure by Letters Patent, is—

1. A vertically-adjustable separating-rod or cut-off, vibrating in a circular horizontal path, substantially as set forth.
2. A separating-rod or cut-off, vibrating horizontally in a curved path, and adjustable horizontally relatively to the finger-beam, substantially as set forth.
3. A separating-rod or cut-off, vibrating horizontally, and capable of adjustment at an angle to the finger-beam, substantially as set forth.
4. The combination, substantially as set forth, of a reel with a separating-rod, vibrating horizontally over the platform.
5. The combination, substantially as set forth, of a dropping-platform with a separating-rod, vibrating horizontally over the platform.
6. The combination, substantially as set forth, of an overhung reel, a dropping slatted platform, and a horizontally-vibrating separating-rod.
7. The combination of a horizontally-vibrating separating-rod, supported at one end only with a finger-beam hinged to the main frame.
8. The combination, in a harvester, of a laterally-projecting hinged finger-beam, a reel, a platform, and a horizontally-vibrating cut-off, when the three latter are mounted on the finger-beam and shoe only.
9. The combination of a dropping-platform with a horizontally-vibrating cut-off, when so arranged that the dropping of the platform interposes the cut-off, and the raising of the platform withdraws it.

In testimony whereof, I have hereunto subscribed my name.

AMOS RANK.
